UNITED STATES PATENT OFFICE.

BEN ZION HAUSNER, OF NEW YORK, N. Y.

SNAP-BUTTON.

1,167,753.

Specification of Letters Patent. Patented Jan. 11, 1916.

Application filed September 8, 1915. Serial No. 49,490.

To all whom it may concern:

Be it known that I, BEN ZION HAUSNER, a citizen of the United States, and a resident of New York city, in the county and State of New York, have invented certain new and useful Improvements in Snap-Buttons, of which the following is a specification.

This invention relates to a snap button and more particularly to a novel construction of the female member thereof, which is characterized by extreme flatness, so that the device possesses superior merits whenever the height of the button constitutes an important factor as it frequently does.

In the accompanying drawing: Figure 1 is a plan of the female member of a snap button embodying my invention; Fig. 2 a plan of the male member; Fig. 3 a section on line 3—3 Fig. 1; Fig. 4 a cross section of the button showing it closed; Fig. 5 a plan of a modification of the female member; Fig. 6 a section on line 6—6 Fig. 5; Fig. 7 a plan of a further modification; Fig. 8 a section on line 8—8 Fig. 7, and Fig. 9 a plan of a still further modification.

The male member of the button may consist of a rounded head 1, having a neck 2, and projecting from a plate 3, having thread holes 4, all as usual.

The female member of the button, to which my invention more particularly relates, consists of a sinuous wire or similar resilient strip of material, which is so bent as to form a plurality of salient or outer loops 5, and a plurality of intervening re-entrant or inner loops 6, the outer loops being normally closed at their mouths or points of merger into the inner loops, whereby the play of the device is checked. The entire length of the wire is laid out in a common plane, and its ends are preferably joined in suitable manner, so that it is endless, and represents somewhat a stellated appearance. The outer loops 5 may be of rounded or other contour, but the inner loops 6, are preferably slightly elongated or flattened at their bight, and form between them, a central opening 7 having arched sides and adapted to receive the head 1 of the male member. The wire formed as

described, is incased within a suitable frame which projects over the outer loops 5, but clears the inner bars of the inner loops 6. This frame may be of suitable design or 55 construction, both of its sides being however, flattened against the corresponding sides of the wire, so that the entire device is flat at its front and back and is consequently reversible. In Figs. 1-4 it is shown 60 to consist of a grooved rim 8, that straddles the ends of loops 5 and is furnished with thread holes 9 between the outer loops. In Figs. 5 and 6, it is shown to be composed of an annular disk 10, furnished with a 65 flange 11, so as to likewise straddle loops 5. In Figs. 7 and 8, it is shown to be composed of a pair of annular disks 12, which are connected along their periphery, while in Fig. 9 it is shown to consist of a square 70 frame 13, having flange 14.

In practice the head 1 is forced into opening 7, so as to temporarily spread loops 6, and cause them to snap into engagement with neck 2, as soon as the head has cleared 75 the loops. During this operation, the resiliency of the entire length of wire will come into play, inasmuch as all of the inner loops merge into the bodies of the outer loops, which are thus slightly opened 80 up by the pressure of head 1.

It will be seen that the button constructed as described, when sewn to a garment or other article, will have its female member arranged in a plane parallel to such article 85 and that the flatness of such female member will be such, as not to materially add to the thickness of the latter. So also the female member may be sewed to the garment with either side up. 90

I claim:

In a snap button, a female member composed of a continuous strip of resilient material formed of a plurality of normally closed outer loops and a plurality of intervening inner loops all arranged in a common plane, and of a frame having flattened sides that engage the corresponding sides of the outer loops, the entire device being 95 flat on the front and back and reversible.

BEN ZION HAUSNER.
